BASEBALL BATTING CAGE

William H. Heeremans, Princeton, N.J.

Application September 19, 1956, Serial No. 610,830

5 Claims. (Cl. 273—26)

The present invention relates generally to athletic equipment and devices, and particularly is directed to a new and improved baseball batting cage structure.

At present a number of baseball batting cages of various different types are used by various professional and amateur organizations. The primary purpose in using 20 batting cages is to reduce the considerable financial loss occasioned by loss of baseballs during batting practice. There are, of course, other advantages to be realized in using batting cages such as, for example, the convenience of not having to retrieve errant foul drives and also the 25 fact that it is not necessary to use a catcher during batting practice.

Some of these cages are relatively small in size and simple in structure but serve only to stop low foul balls which are deflected by the batsman immediately to the 30 rear of home plate. Other cages are somewhat larger and stop higher foul balls and some balls which are fouled to either side of the plate. However, in general, the larger cages are rather complicated mechanically and therefore are difficult to assemble for quick use. Furthermore, they usually are quite awkward and cumbersome in appearance and design and are difficult to move about from place to place. Additionally, these cages often require an excessive amount of storage space when 35 they are not in use.

An object of the present invention is to provide a new and improved baseball batting cage.

Another object of the invention is to provide an improved batting cage having features of construction which are designed to reduce the number of baseballs lost during batting practice.

A further object of the invention is to provide an improved batting cage which may be at least partially collapsed when not in use, and which may be erected for use simply and quickly.

A still further object of the invention is to provide a cage of the above type which is readily movable and occupies very little storage space when not in use.

The foregoing and other objects and advantages are achieved in accordance with the invention by providing a batting cage frame in which a plurality of rigid substantially U-shaped frame members are mechanically joined together at or near their respective open ends. By joining the U-shaped members together in this manner, the members thereby are pivotally connected. The pivotally connected members then may be successively pivoted into position and secured in place by means of spacer bars and a net may be fastened to each of the frame members to form a hood-like enclosure.

When the cage is not in use and is to be stored it is necessary only that spacer bars be detached from the U-shaped frame members. The pivotally joined U-shaped members then collapse and are foldable along each other and the device occupies very little storage space.

The design of the cage is such that when it is erected for use the bottom portion of the cage rests flat on the surface of the baseball diamond. This feature of design

obviates the possibility that low foul balls on or near the ground may escape from the cage. However, notwithstanding the fact that the bottom portion of the cage rests flat on the surface of the diamond and the further fact that the cage is relatively large in size, means are provided whereby wheels readily may be affixed to the cage without undue physical effort so that the cage easily may be moved from place to place.

The invention will be described in detail with reference to the accompanying drawings in which:

Figures 1 through 4 are pictorial representations of a baseball batting cage, fabricated in accordance with the invention, wherein the cage is shown in successive stages of erection for use;

Figure 5 is a detailed view illustrating the manner in which wheels are connected to the cage shown in Figures 1 through 4 to render the batting cage movable;

Figure 6 is a front view of the lower portion of the cage; and,

Figure 7 is a view illustrating the manner in which the spacer bars are snap-fastened onto the frame of the batting cage.

Similar reference numerals are applied to similar elements throughout the drawings.

Referring to Figure 1, and according to a typical embodiment of the invention, a baseball batting cage is shown in assembled form which is to be erected for use.

The cage includes a base section comprising a pair of substantially identical rigid U-shaped frame members 11 and 13 which have their open ends mechanically joined together by means of their being bolted or otherwise connected between two pairs 15 and 17 of spaced rectangular plates. The U-shaped members 11 and 13 preferably are formed from a durable rust-proof metal such as an aluminum or other light-weight alloy and comprise lengths of hollow pipe or tubing. While each of the members 11 and 13 may constitute relatively long single lengths of pipe or tubing, for practical reasons it may be more feasible to employ for each member shorter lengths of pipe joined by suitable fittings. The open ends of the members 11 and 13 are connected between the pairs of plates 15 and 17 in such a manner that the members 11 and 13 are free to pivot with respect to each other in a vertical direction. While other types of coupling may be employed for mechanically joining together the frame members 11 and 13, the rectangular plate arrangement is particularly effective inasmuch as it additionally affords desired mechanical strength at the point of connection.

The frame members 11 and 13 of the base are spaced a predetermined distance apart by means of different lengths of pipe or tubing 19, 21, and 23 connected between the frame members at substantially opposite spaced points along their respective lengths. The members 19, 21, and 23 are connected to the U-shaped frame members 11 and 13 by means of cross-fittings.

A further U-shaped frame member 25 is provided which is substantially identical to the frame members 11 and 13 of the base section. This member 25 also has its open ends connected between the pairs of plates 15 and 17 and is coupled to the base section so that it is pivotal with respect thereto.

The cage further includes another pair of substantially identical U-shaped frame members 27 and 29 which are like the members 11, 13, and 25 in all respects except that the legs of the members 27 and 29 are shorter than the legs of the members 11, 13, and 25. These frame members 27 and 29 have their open ends pivotally connected to the frame member 13 of the base section by mechanical couplings 31 which are spaced from the plates 15 and 17 a distance approximately equal to the difference in the lengths of the legs referred to above. Specifically, and by way of example, these couplings 31 comprise aper-

tured disks bolted or otherwise secured to the base at the point indicated, and the open ends of the members 27 and 29 are connected to these disks.

The cage is provided with a net 33 which is fastened to each of the U-shaped frame members so that when the cage is ready for use the cage is wholly enclosed and foul balls cannot escape from the confines of the cage.

To initiate the erection of the cage for use, a pair of bars 35 of the type shown in Figure 2 are employed. These bars comprise lengths of hollow pipe or tubing of the type used in the U-shaped frame members, and the bars have their ends semi-circularly formed, as shown in Figure 7, to seat on and around a portion of the peripheries of the frame members 25 and 29. The concave portion of each semi-circularly formed end has projecting therefrom a spring-actuated pin 30 which automatically is depressed when one of the bars 35 is snapped onto a frame member such as the member 25 and, after the bar 35 is properly seated thereon, the pin automatically springs back to its original position and locks the bar onto the frame member.

Thus, after one end of each of the two bars 35 is connected to the frame member 25 in the manner described above, the remaining ends of the bars 35 are grasped by the person erecting the cage and used to pivot the frame member 25 upwardly. The remaining ends of the bars 35 are then locked onto the next frame member 29. Then, as shown in Figure 3, another pair of bars 37, similar to the bars 35, have two of their ends locked onto the frame member 29, and the free ends of the bars 37 are utilized to pivot the frame member 29 into position (and also simultaneously advance the position of the frame member 25). The free ends of the bars 37 then are locked onto the next frame member 27. Then, and as shown in Figure 4, a still further pair of bars 39 is used to pivot the frame member 27 into position and to advance the positions of the frame members 25 and 29. The free ends of the bars 39 are then snapped and locked onto the frame member 13 of the base of the cage. When this operation is completed, the cage is fully erected and ready for use.

When the cage is not in use and is to be stored it is necessary only that one reverse the procedure for erecting the cage. In such case, the spring-actuated means for locking the bars 39, 37, and 35 are released in order and the bars detached from the U-shaped frame members. The frame members then collapse and fold along each other on the base section and the cage occupies a minimum of storage space.

Figure 5 shows in detail the manner and means by which the batting cage of Figures 1 through 4 is rendered movable or portable. According to this aspect of the invention a sleeve 41 is connected to the frame member 11 at a point between the pair of plates 15 and one of the base support members 19. The wheel assembly adapted to be connected to the sleeve 41 comprises a wheel 43 having an axle 45 to which one end of a lever arm 47 is connected. One portion of the arm 47 extends radially from the axle 45 of the wheel 43 a distance slightly greater than the radius of the wheel. The remaining portion of the arm extends at an obtuse angle with respect to the radial portion, this angle being from about 130° to 140°. At the vertex of the obtuse angle formed by the two portions of the arm 47 a shaft 49 extends perpendicularly from the side of the lever arm which is most remote from the wheel. The longitudinal axis of this shaft 49 is parallel to but not concentric with the axis of the axle 45.

Because of the fact that the bend in the lever arm 47 occurs at a point along the length of the arm which is further from the center of the axle 45 than the radius of the wheel 43, the shaft 49 may be inserted in the sleeve 41, notwithstanding the fact that the batting cage rests flat on the surface of the baseball diamond. The other end of the lever arm 47 may then be turned in a counter-clockwise direction until it contacts a mechanical stop 51.

The eccentric relation of the shaft 49 and the axle 45 results in one side of the cage being elevated off the ground when the lever arm 47 is manipulated as described. By a substantially identical arrangement, which will not be described in the interest of avoiding undue repetition, the other side of the cage may have a similar wheel assembly connected thereto.

In Figure 6 a front view of the lower portion of the batting cage is shown which illustrates the use of a canvas or tarpaulin 53 across the back part of portion of the base section. The canvas or tarpaulin reduces the extra-heavy wear and tear inflicted on the portion of the net immediately to the rear of the batsman. The figure additionally shows a portion of a two-wheeled dolly 55 which is adapted to be connected by some such means as a trailer hitch to the central part of the closed end of the U-shaped member 11. When the side wheels 43 and the dolly 55 are connected to the cage, the dolly may be used to move and guide the cage to whatever location is desired.

What is claimed is:

1. A baseball batting cage frame comprising, a base for said frame adapted to rest flat on the surface of a baseball diamond including a rigid U-shaped member, a plurality of additional rigid substantially U-shaped members each having one free end pivotally connected to one leg of said first-named U-shaped member at a point along the length of said one leg which is nearer to the open end of said first-named member than to its closed end and the other free end pivotally connected to the remaining leg of said first-named member at a point along the length of said remaining leg which is substantially opposite said first-named point, and a spacer bar for connection between adjacent ones of said additional U-shaped members for maintaining a predetermined spacing between said adjacent members, each end of said spacer bar being semi-circularly shaped to seat on and around a portion of the periphery of said U-shaped members and including a spring-actuated pin extending from the concave surface of said semi-circularly shaped end.

2. A baseball batting cage frame as claimed in claim 1 wherein said base includes means for receiving a wheel assembly for moving said cage.

3. A baseball batting cage frame comprising; a base for said frame adapted to rest flat on the surface of a baseball diamond including, a first pair of substantially identical rigid U-shaped members, means for mechanically joining the open ends of said pair of U-shaped members so that said members are pivotally connected together, and a plurality of rigid spacer members for maintaining a predetermined spacing between said pair of U-shaped members; a further rigid U-shaped member, substantially identical to the U-shaped members in said base, having its open ends connected to said mechanical joining means of said base so that said further member is pivotally connected to said base; a second pair of substantially identical rigid U-shaped members similar to said first-named U-shaped members except that the legs of said second-named pair of U-shaped members are shorter than the legs of said first-named U-shaped members; means connected to one of the U-shaped members of said base, and spaced from the open end of said member a distance approximately equal to the difference in length between the members of said pairs of U-shaped members, for pivotally connecting said second-named pair of U-shaped members to said base; and, a spacer bar for connection between said base and the pivotal U-shaped member adjacent thereto and a spacer bar for connection between adjacent pivotal U-shaped members for maintaining a predetermined spacing between said members, each end of each of said spacer bars including means for snap-fastening said bars to said adjacent U-shaped members.

4. A baseball batting cage frame comprising, a base for said frame adapted to rest flat on the surface of a

baseball diamond including a rigid U-shaped member, a plurality of additional rigid substantially U-shaped members each having one free end pivotally connected to one leg of said first-named U-shaped member at a point along the length of said one leg which is nearer to the open end of said first-named member than to its closed end and the other free end pivotally connected to the remaining leg of said first-named member at a point along the length of said remaining leg which is substantially opposite said first-named point, and a spacer bar for connection between adjacent U-shaped members for maintaining a predetermined spacing between said members, each end of said spacer bar being semi-circularly shaped to seat on and around a portion of the periphery of said U-shaped members and including a spring-actuated pin extending from the concave surface of said semi-circularly shaped end.

5. A baseball batting cage frame comprising; a base for said frame adapted to rest flat on the surface of a baseball diamond including, a first pair of substantially identical rigid U-shaped members, means for mechanically joining the open ends of said pair of U-shaped members so that said members are pivotally connected together, and a plurality of rigid spacer members for maintaining a predetermined spacing between said pair of U-shaped members; a further rigid U-shaped member, substantially identical to the U-shaped members in said base, having its open ends connected to said mechanical joining means of said base so that said further member is pivotally connected to said base; a second pair of

20

25

30

substantially identical rigid U-shaped members similar to said first-named U-shaped members except that the legs of said second-named pair of U-shaped members are shorter than the legs of said first-named U-shaped members; means connected to one of the U-shaped members of said base, and spaced from the open end of said member a distance approximately equal to the difference in length between the members of said pairs of U-shaped members for pivotally connecting said second-named pair of U-shaped members to said base; and, a spacer bar for connection between said bar and the pivotal U-shaped member connected thereto and a spacer bar for connection between adjacent pivotal U-shaped members for maintaining a predetermined spacing between said members, each end of said spacer bar being semi-circularly shaped to seat on and around a portion of the periphery of said U-shaped members and including a spring-actuated pin extending from the concave surface of said semi-circularly shaped end.
